Patented Oct. 26, 1920.

UNITED STATES PATENT OFFICE.

LELAND D. SLUSSER, OF OTTAWA, OHIO.

INTERNAL-COMBUSTION ENGINE.

1,356,792.

Specification of Letters Patent. Patented Oct. 26, 1920.

Application filed June 28, 1920. Serial No. 392,291.

To all whom it may concern:

Be it known that I, LELAND D. SLUSSER, a citizen of the United States, residing at Ottawa, in the county of Putnam and State 5 of Ohio, have invented a new and useful Internal-Combustion Engine, of which the following is a specification.

This invention relates to internal combustion engines and has for its object the 10 provision of novel valve mechanism whereby intake and exhaust gases are conducted through a single tappet valve located in the head of the cylinder.

With this and other objects in view 15 which will appear as the description proceeds and as particularly pointed out in the appended claim, the invention resides in the combination and arrangement of parts hereinafter pointed out, it being understood that slight changes may be made within the scope of what is claimed without departing from the spirit or sacrificing any of the advantages of the invention.

In the drawing there is illustrated a view 20 in elevation partly in section of an engine constructed in accordance with the present invention.

Referring to the drawing 1 designates the crank case and 2 the cylinder of an 25 internal combustion engine the same being of ordinary and well known construction. A crank shaft 3, connecting rod 4 and piston 5 are also of the usual design.

Located to one side of the crank case is 30 an auxiliary casing 6 which houses the valve operating mechanism. This mechanism comprises a cam shaft 7 having a crank 8, on which is mounted a connecting rod 9. A cam 10 is secured to the shaft 40 7 and operates a roller 11 to lift a push rod 12.

The head 13 of the cylinder 2 is provided with a wall 14 having a valve seat 15 formed therein and a tappet valve 16 45 is urged to seat at 15 under the action of a spring 17. A lever 18 fulcrumed at 19 is actuated by the push rod 12 to open the valve 16.

A piston valve casing 20 is secured to 50 the cylinder 2 and is connected to the casing 6 by an expansion sleeve 21. The bore 22 of the casing 20 is open at both ends and is fitted with a piston 23. A passage 24 is formed in the piston 23 and is adapted 55 to establish communication between the

cylinder 2 and a source of fuel supply through a port 25 in the casing 20 and a port 26 in the cylinder head 13. Reciprocation of the piston 23 is effected by the crank 8 through the connecting rod 9. 60

Timing gears 27 and 28 of a two to one ratio are mounted on the shafts 3 and 7 respectively and operate the valves in timed relation with the reciprocation of the piston 5. 65

The operation of the engine is as follows, assuming that the engine has just finished the exhaust stroke with the parts in the position illustrated in the drawing and moving in the direction indicated by 70 the arrows. The piston valve 23 moving upwardly opens the port 25 leading from the carburetor (not shown) to the cylinder 2, through the passage 24, the piston 5 now on its downward or suction stroke draws 75 in a charge of gas, when the piston reaches the bottom of its stroke the cam 10 leaves the roller 11 and the valve 16 closes for the compression stroke of the piston, remaining closed until the power stroke is 80 complete. During this movement of the piston 5 the shaft 7, has made a partial rotation and the cam 10 under-rides the roller 11 to open the valve 16, the piston valve 23 having also moved to uncover the 85 port 26 and permit the exhaust gases to escape to the atmosphere through the open end of the bore 22. 85

Although the engine has been described in the singular it is to be understood that 90 any number of cylinders may be employed. It will also be observed that because of the use of but one valve through which intake and exhaust takes place, the same may be of maximum size, this being especially 95 advantageous during the exhaust stroke of the piston as will be readily understood. Further, intake of fresh gas occurring as it does through the same valve through which the burned gases escape, tends to 100 keep the engine cool, also to keep the valve seat clean and free of carbon deposits. Exhaust of the engine is also facilitated by the proximity of the cylinder to the 105 large opening through the end of the bore 22.

Having thus described the invention what is claimed is:—

An internal combustion engine comprising a cylinder having a combined intake 110

and exhaust passage; a first valve controlling the passage; a source of fuel supply; a second valve consisting of a cylinder, and a piston mounted therein, the cylinder having communication with the passage, the piston having a passage whereby communication between the source of fuel supply and the intake passage is established and adapted to move to a position to permit 10 exhaust through the cylinder of the second

valve; and means for operating the valves in timed relation.

In testimony that I claim the foregoing as my own, I have hereto affixed my signature in the presence of two witnesses.

LELAND D. SLUSSER.
